Specification for Design.

Patented Feb. 13, 1912.

Application filed November 2, 1911. Serial No. 658,282. Term of patent 7 years.

To all whom it may concern:-

Be it known that I, FISHER H. LIPPINCOTT, a citizen of the United States, residing in the city of Philadelphia, county of Philadelphia, and State of Pennsylvania, have invented a new, original, and ornamental Design for Faucets, of which the following is a specification, reference being had to the accompanying drawings, forming part thereof.

In the drawings, Figure 1 is a perspective view of a faucet embodying my new design, and Fig. 2 is a side elevation of the same.

As represented in the drawings, the faucet embodying my design comprises the body 1, a neck 2 extending laterally therefrom, a nozzle 3 extending downwardly therefrom, an arch 4 thereon, and a handle 5 extending outwardly from the arch.

I claim:

The ornamental design for a faucet as shown and described.

FISHER H. LIPPINCOTT.
